UNITED STATES PATENT OFFICE.

WARREN E. COOPER, OF FLUSHING, NEW YORK, AND VICTOR WILLOUGHBY, OF RIDGEWOOD, NEW JERSEY, ASSIGNORS TO AMERICAN CAR AND FOUNDRY COMPANY, OF NEW YORK, N. Y., A CORPORATION OF NEW JERSEY.

MULTIPLE-UNIT TANK CAR.

Application filed February 15, 1924. Serial No. 693,002.

In the drawings:

Fig. 1 is a view in perspective of a portion of a multiple unit tank car constructed in accordance with this invention; and
5 Fig. 2 is a central vertical section of one end of a tank unit and the means for securing the tank unit to the car.

It is an object of this invention to provide an improved multiple unit tank car of the 10 type in which the tank units are removed from the car for charging and discharging and it is also an object of this invention to provide an improved means for securing the tank units to the car body which may be 15 readily operated to secure or release the tank units and which may be readily applied and removed from the car. It is also an object of this invention to provide a securing means suitable for securing individual tank 20 units and which will be of simple and inexpensive construction.

In the drawings, this invention is shown as applied to the floor 1 supported by the underframe 2 of a flat car of ordinary construction, but it is to be understood that this invention may be applied to any car having a suitable flat floor. To the floor 1 spaced rows of hinge brackets 3 are secured by bolts 4 or other suitable means, the rows 25 of hinge brackets 3 being spaced sufficiently far apart to admit of the placing of cylindrical containers or tank units 5 between the rows. The rows of hinge brackets are grouped in pairs, the pairs at the two sides 30 of the car being placed opposite and each pair being designed to pivotally support a securing structure or keeper in the form of a pressed diaphragm 6 provided with a pivot 7 which engages in the openings 8 in the hinge brackets. The diaphragms 6 have their central portions pressed inwardly, as at 7, forming shoulders 16 which are adapted to engage with the inside of the greater portion of the edges of the recessed or reentrant ends 15 of the tank units, 40 both above and below the center, each portion extending from slightly above the floor around the upper portion of the end and down to a point opposite the starting point, 45 thus substantially conforming to the tank end perimeters and giving the diaphragms contact with the ends of the tank units 50 which enables the diaphragms to prevent

movement of the tank units in any direction. It will be noted, as shown in Fig. 2, that 55 the projecting portions of the diaphragms do not project into the ends of the tank units far enough to engage with the covers 8 over the filling and discharge outlets 9. The diaphragms at their upper ends are provided with upwardly projecting portions 10 having slots 14 adapted to receive rods 11 which rest in the slots 14 and directly interconnect or intercouple the diaphragms at the opposite ends of each tank unit, the rods 65 11 being provided with nuts 12 at each end which engage with the diaphragms 6 and which serve to force the diaphragms 6 into engagement with the ends of the tank units. The rods 11 are of sufficient length to permit 70 loosening of the nuts 12 sufficiently to release and disengage the rods 11 from the slots 14 of the diaphragms 6 and have their ends headed to prevent loss of the nuts 12. When one of the nuts 12 of a rod 11 is 75 tightened up, the rod draws on each of the diaphragms 6 against the other, thus holding or clamping them together on the tank.

Assuming the car to be empty and the rods 11 removed from the diaphragms 6 in 80 order to load the car, the diaphragms will be laid down in the position shown in dotted lines in Fig. 1, the tank units 5 placed on the car between the diaphragm hinges and in line therewith, and the diaphragms 6 85 brought up into engagement with the ends of the tank units and secured thereto by adjusting the nuts 12 on the rods 11 which are placed in the slots 14 in the diaphragms 6. To unload the tank units 5 from the car the 90 nuts 12 of the rods 11 are unscrewed, releasing the rods 11 and permitting their withdrawal from the slots 14 in the diaphragms 6, whereupon the diaphragms 6 are 95 laid down into the position shown in dotted lines in Fig. 1, which leaves the tank free for handling with the usual hoisting means or in any desired manner.

What is claimed is:

1. In a multiple unit tank car, a supporting means, tank units carried by said supporting means, securing members for said tank units pivotally mounted on said supporting means at the ends of each tank unit and means directly interconnecting the securing members of each tank unit, so as to 100
- 105

draw on each against the other in forcing them into engagement with said tank unit.

2. In a multiple unit tank car, the combination with the car structure and tanks thereon, of substantially rigid securing structures hinged directly to the car structure at the opposite ends of the tanks, and means extending between and directly connecting said securing structures for retaining the latter in engagement with the ends of said tanks.

3. In a multiple unit tank car, a supporting means, a tank unit carried by said supporting means, hinge brackets secured to said supporting means at the ends of said tank units, diaphragms pivotally mounted in said hinge brackets, and means directly and adjustably interconnecting the diaphragms of each tank unit for drawing them together on said tank unit.

4. In a multiple unit tank car, a floor, a cylindrical container carried by said floor, slotted dished diaphragms pivotally mounted on said floor at the ends of said container and means engaging in the slots in said diaphragms for holding them in engagement with the ends of said container.

5. In a multiple unit tank car, a car floor, a cylindrical container carried by said floor, slotted dished diaphragms pivotally mounted on said floor, and means connecting said diaphragms engaging in said slots and adapted to force said diaphragms into engagement with said container to secure said container against movement in any direction.

6. In a multiple unit tank car, a supporting means, a tank unit carried by said supporting means, diaphragms pivotally secured to said supporting means at the ends of said tank unit and means interconnecting said diaphragms, so as to draw on each against the other in forcing them into engagement with the ends of said tank units.

7. In a multiple unit tank car, a supporting means, a tank unit carried by said supporting means, dished diaphragms pivotally secured to said supporting means and adapted to engage at the ends of said tank unit and means connecting said diaphragms adapted to hold said diaphragms in engagement with said tank unit to secure said tank unit in position.

8. In a multiple unit tank car, a floor, cylindrical containers carried by said floor, securing members for said containers pivotally mounted on said floor and means connecting said securing members adapted to hold said securing members in engagement with said containers to secure said containers in position.

9. In a multiple unit tank car, a floor, a cylindrical container carried by said floor, securing members pivotally mounted on said floor at the ends of said container and

a rod adapted to connect said securing members and force them into engagement with said container.

10. In a multiple unit tank car, a supporting means, a cylindrical container carried by said supporting means, co-operating securing members at the ends of said containers and means directly interconnecting said securing members adapted to draw on each against the other to render them operative to secure said container in position.

11. In a multiple unit tank car, a supporting means, a container carried by said supporting means, co-operating securing members pivotally mounted on said supporting means and means directly interconnecting said securing members adapted to draw on each against the other to render said securing members operative.

12. In a multiple unit tank car, a supporting means, a container carried by said supporting means, securing means mounted on said supporting means at the ends of said container, and a rod extending from end to end of said container and connecting said securing means to secure said container in position.

13. In a multiple unit tank car, a supporting means, a container carried by said supporting means, dished diaphragms on said supporting means and a rod extending from end to end of said container and adjustable to secure said diaphragms in engagement with said container.

14. In a multiple unit tank car, a support, a container carried by said support, members mounted on said support adjacent the ends of said container and means extending from end to end of and above said container and engaging said members with said container.

15. In a multiple unit tank car, a support, a container carried by said support, dished diaphragms mounted on said support adjacent the ends of said container and adjustable means extending from end to end of said container and securing said diaphragms in engagement with said container.

16. In a multiple unit tank car, a support, a tank unit carried by said support, means for securing said tank unit mounted on said support and a rod extending from end to end of said tank unit adapted to force said securing means into engagement with said tank unit.

17. In a multiple unit tank car, a support, a tank unit carried by said support, means carried by said support for securing said tank unit in position and engaging the ends of said tank unit, and means extending from end to end of and above said tank unit connecting said means and adapted to force said means into engagement with said tank unit.

18. In a multiple unit tank car, a support, a container carried by said support, diaphragms mounted on said support adjacent the ends of said container and means wholly carried by said diaphragms adapted to force said diaphragms into engagement with said container.
19. In a multiple unit tank car, the combination with the car of a tank recessed at its ends and keepers internally engaged in the opposite ends, both above and below the center, to hold it in place against movement in any direction.
20. In a multiple unit tank car, the combination with the car of a tank recessed at its ends, keepers movably mounted on the car for internally engaging in the opposite ends of the tank, both above and below the center, and means releasably intercoupling said keepers to hold them together in engagement with the tank.
21. In a multiple unit tank car, the combination with the car of a tank recessed at its ends, keepers hinged to the car at the opposite ends of the tank for internally engaging them, both above and below the center, and means for releasably holding said keepers in engagement.
22. In a multiple unit tank car, the combination with the car of a tank with reentrant ends and keepers engaging in the tank ends and conforming substantially to their perimeters, for holding the tank in place against movement in any direction.
23. In a multiple unit tank car, the combination with the car of a tank with reentrant ends, keepers movably mounted on the car engaging in the tank ends and conforming substantially to their perimeters, and means for releasably and adjustably drawing said keepers together on the tank.
24. In a multiple unit tank car, a supporting means, a tank unit carried thereby, hingedly mounted rigid securing structures carried by the support and engaging the ends of the tank unit when in elevated position, and means extending across the tank unit and connecting the securing structures when in elevated position for retaining the latter in engagement with the ends of the tank unit.
25. A multi-unit tank car comprising a car structure, a plurality of tanks mounted on said car structure transverse to the longitudinal axis thereof, a plurality of hingedly mounted securing structures carried by the car structure and arranged in pairs, each pair being adapted to engage the ends of a tank when said structures are in elevated position, and means removably connecting the securing structures when the latter are in elevated position for retaining said securing structures in engagement with the tank ends.
26. A multi-unit tank car comprising a car structure, a plurality of tanks mounted thereon transverse to the longitudinal axis thereof, a plurality of hingedly mounted securing structures carried by the car structure and arranged in pairs, each pair being adapted to engage the ends of a tank when said structures are in elevated position, and adjustable means removably connecting the securing structures when the latter are in elevated position and extending longitudinally of the tanks from end to end when the said securing structures are in elevated position for retaining the securing structures in engagement with the tank ends.

In witness whereof we have hereunto set our hands.

WARREN E. COOPER.
VICTOR WILLOUGHBY.
